H. B. WRIGHT

CIGARETTE HOLDER

Filed July 10, 1925

Lacy Lacy, Attorney

UNITED STATES PATENT OFFICE.

HARRY B. WRIGHT, OF LONG BEACH, CALIFORNIA, ASSIGNOR OF ONE-HALF TO PERRY L. WRIGHT, OF LONG BEACH, CALIFORNIA.

CIGARETTE HOLDER.

Application filed July 10, 1925. Serial No. 42,839.

This invention relates to an improved cigarette holder and seeks, among other objects, to provide a device of this character which may be attached to a desk, table, or 5 to the instrument board of an automobile, for instance, for keeping a supply of cigarettes conveniently accessible.

The invention seeks, as a further object, to provide a device embodying means for 100 ejecting the cigarettes one at a time from the holder, and wherein only one hand of the operator will be required to actuate said ejecting means so that even though one hand is employed in driving the vehicle, a cigarette 15 may, nevertheless, be obtained with the other hand.

And the invention seeks, as a still further object, to provide a device which will be simple in construction and which may be 20 readily reloaded.

Other objects of the invention not above specifically mentioned will appear as the description proceeds.

In the accompanying drawings:

25 Figure 1 is an elevation showing the holder attached to the instrument board of a conventional motor vehicle, a portion of the casing being broken away to show the mounting of the ejecting plunger.

30 Figure 2 is a transverse sectional view on the line 2—2 of Figure 1, looking in the direction indicated by the arrows.

Figure 3 is a vertical sectional view on the line 3—3 of Figure 1, looking in the direction indicated by the arrows.

35 In carrying the invention into effect, I employ a flat oblong casing which is preferably of sheet metal and is provided with a front wall 10 and parallel side walls 11, the casing being open at its ends as well as 40 back thereof. As shown in Figure 2, the side walls 11 are bent to form longitudinal channels 12, and fixed to said side walls are brackets 13 adapted to receive screws or 45 other fastening devices mounting the holder. In the present instance, I have shown the holder attached to the instrument board 14 of a conventional motor vehicle and, as will be observed, said holder is located near one 50 end of the instrument board so as to be readily accessible to the driver of the vehicle.

55 Slidable through the side walls 11 near the lower end of the casing is a plunger including an ejector rod 15 which is offset to form a shoulder 16 to abut the adjacent side

wall 11 of the casing, and fixed to the adjacent end of said rod is a knob 17. Near its opposite end, the rod is bent back to form an inwardly directed terminal 18 which extends freely through the other side wall of 60 the casing in parallel relation to the intermediate reach of the rod, and surrounding said terminal is a spring 19 normally holding the rod retracted.

Mating with the casing is a carrier 20 65 closing the casing. The carrier is also preferably of sheet metal and, as shown in Figure 2, is offset near its longitudinal margins to define flanges 21 slidably fitting in the channels 12 of the casing. Thus, the carrier 70 may be readily slid into the casing or removed therefrom, and formed on the carrier at its upper end is an end flange 22 overhanging the front wall 10 of the casing to engage therewith for limiting the carrier in 75 its downward movement into the casing. The overhanging margin of this flange may also be readily grasped for sliding the carrier upwardly out of the casing. At its lower end, the carrier is provided with a 80 flange 23 which lies close to the ejector rod 15 near the lever of the lower end of the shoulder 16, and, as shown in Figure 1, said flange is cut away at one end to accommodate the travel of said shoulder when the rod is 85 reciprocated. Formed in the adjacent side wall of the casing at the opposite end of said flange is a delivery opening 24.

In use, the carrier 20 is lifted upwardly 90 from within the casing and a supply of cigarettes, as shown at 25, is laid one upon the other within the carrier. The carrier is then returned to its normal position when, as will be seen, the cigarette at the lower end of the carrier is disposed in front of the 95 shoulder 16 of ejector rod 15 opposite the delivery opening 24 of the casing. Accordingly, by pressing on the knob 17, the rod may be pushed forwardly, when said shoulder will partially eject the cigarette through 100 said opening. The projecting end of the cigarette may then be readily grasped and the cigarette entirely removed and, as each cigarette is removed, the next adjacent cigarette will, of course, drop down to rest on the 105 flange 23 of the carrier ready to be ejected.

Having thus described the invention, what I claim is:

1. A cigarette holder, comprising a front wall having opposite longitudinal edge por-

- tions bent laterally in the same direction to form side walls, and having the marginal portions of the side walls bent outwardly and retrorsely to provide channels and a
- 5 back having its longitudinal edge portions offset to provide flanges which are slideable in the said channels, and having the portion comprised between the channels disposed between the side walls and inset from the chan-
- 10 nels.
2. In a cigarette holder, the combination of a casing comprising a front, a back and side walls, the latter having openings, a rod having an end portion offset to provide a
- 15 shoulder which constitutes a stop and an ejector, the end beyond the shoulder passing through the opening in the adjacent side wall, and the opposite end being retrorsely bent and passing through openings in the opposite side wall, and a coil spring mounted upon the retrorsely bent end of the rod and operating to hold the rod retracted.
3. In a cigarette holder, comprising a casing having openings in its side walls, a carrier slideable within the casing and having an inner flange at its lower end, and having an end portion of the flange cut away, a rod slideable in the openings of the side walls, and having an end portion retrorsely bent, and having the opposite end portion offset to
- 25 provide a stop and cigarette ejecting shoulder, and a spring mounted upon the retrorsely bent end of the rod and operating to normally hold the rod retracted.

In testimony whereof I affix my signature.
HARRY B. WRIGHT. [L. S.]
